GLASS EDGING MACHINE

William Owen, Pittsburgh, Pa., assignor to Pittsburgh Plate Glass Company, a corporation of Pennsylvania

Application April 13, 1934, Serial No. 726,421

10 Claims. (Cl. 51—74)

The invention relates to machines of the Weber type for edging glass plates, particularly for use in automobile work. Glass of this type requires a rounded or "pencil" edge, and in the Weber type of machine, this work is accomplished by carrying the sheets or plates, either singly or in sets made up of several sheets side by side, over a series of vertical grinding and polishing wheels whose edges are grooved to the curvature required on the edges of the sheets. The present invention involves an improvement whereby the machine may be used to edge not only sheets having straight edges, but also curved edges or a combination of both, such as is called for by an automobile body light, or the like, having rounded corners, thus eliminating the hand labor which has heretofore been necessary in edging corners or other curves. The invention has for its principal objects the provision of an improved machine of the kind specified, (1) in which the Weber machine can be utilized by the addition of simple inexpensive equipment, and which operates as efficiently and satisfactorily in grinding sheets with curved edges as in grinding straight edges; (2) which can be adjusted to grind any kind of a curved edge; and (3) which requires no attention or manipulation on the part of the operators other than the placing of the sheets on the carrier at one end of the machine and their removal therefrom at the other end of the machine. Certain embodiments of the invention are shown in the accompanying drawings, wherein:

Figure 1 is a side elevation partially in section of the apparatus. Fig. 2 is a section on the line II—II of Fig. 1. Fig. 3 is an enlarged side elevation of a detail. Fig. 4 is an end elevation of the construction shown in Fig. 3. And Figs. 5 and 6 are side elevations showing the apparatus in different positions of adjustment so as to grind the edges of sheets of different curvature.

Referring to the drawings, 1 and 2 are a pair of grinding wheels which constitute a part of a series, such wheels being mounted upon axles 3, 3, which are suitably driven. These wheels have an abrading portion 4 provided with a plurality of grooves 5 of the curvature necessary to round the edges of the glass sheets. These grinding wheels work in suitable troughs 6, 6 carrying water or a mixture of abrasive and water. At the sides of the wheels are the runway sections 7, 8 and 9, which are located below the tops of the grinding wheels and are adapted to support the rounded edges of the glass sheets

16 as they are moved along to the wheels and then away from the wheels. The runway sections are made up of the rolls 11 mounted on pins 12, and such pins may be clamped at any desired position longitudinally of the slots 13 so that the runway may be adjusted to meet requirements.

The glass sheets are moved along the runway and over the grinding wheels by means of an endless drag chain having the upper flight 14 and the lower flight 15, such chain being driven 10 by suitable means which are not shown. The upper flight 14 of the chain is carried in a rectangular tube 16 mounted upon brackets 17 spaced along the length of the chain. The lower flight of the chain is carried upon pusher members 18, 15 which in turn ride upon a pair of guide rails 19 and 20 (Fig. 4). The flight 15 of the drag chain is held down against the members 18 by the plates 21 carried by the lower ends of the brackets 17.

The pusher members 18 are in the form of 20 brackets of U-shape, as indicated in Fig. 4, having one side 22 resting upon the rail 19 and the other side, which is of greater length, provided with a pair of forks 23, 23 (Figs. 3 and 4), which fit over the guide rail 19. The pusher member 25 is provided with an upstanding lug 24 (Fig. 3) which fits into one of the open links of the chain so that the member 18 is carried along with the chain. Mounted pivotally on the rod 25 carried by each pusher member is a strap metal 30 frame 26 of U-shape, which can be held at any desired angle with respect to the vertical by means of the clamping nut 27 on the rod 25. The bracket 26 is designed to support a set of 35 glass plates, in the present instance six in number, in such manner that the plates may move up and down freely in a plane which is parallel to the angle of the bracket 26. In order to facilitate this free up and down movement, the bracket is provided with three sets of grooved 40 rollers 28, 29 and 30 mounted upon the pivots 25, 29 and 30. In order to guide the edge of the sheet which is on the pusher member back of the bracket 26 and to brace the bracket, each bracket is provided with two pair of arms 34 and 45 35 the latter carrying the grooved rollers 31. Each glass sheet is thus supported at its two opposite edges in such manner that it is free to move up and down in a right line. The arms 34 are supported upon pivot rods 33, which extend through slots 36 in the brackets 26 and are clamped in position by means of the nuts 46, thus permitting of an adjustment of the arms 35 longitudinally of the brackets 26. Similarly, the arms 34 are slotted as indicated at 41 to 55

receive the pivot 42 upon which the roll 36 is mounted so that the arms may be adjusted and clamped in position by a nut 43 carried upon the pivot. The arms 34 act to brace the bracket 5 26 in the position to which it is adjusted.

Projecting from the end portions 44 of the arms 35 is a series of fingers 45 arranged so that each plate of glass lies between two of such fingers. The ends of these fingers are provided with rubber caps 46 and the fingers serve to steady the plates and hold them in position as they move up and down along the rollers 28, 29 and 30.

10 Similarly, another set of fingers 47 are provided at the lower edges of the sheets, such fingers 15 being secured to the pusher members 18 and serving to properly space and guide the glass sheets at their lower edges. Mounted on the pusher 18 and extending therefrom in the same direction as the arms 35, is a third series of fingers 47a.

20 The fingers 47a serve to steady the lower portion of the glass sheets adjacent the edges guided by the roller 31. In order to press the glass sheets downwardly and give them the necessary grinding pressure upon the wheels, shot bags 48 are placed upon the sets of sheets, as indicated in Fig. 1. Any other suitable means for applying downward pressure to the sheets may be employed and this pressure may be adjusted to suit requirements.

30 Fig. 1 illustrates the apparatus adjusted to grind the lower edges of the glass sheets and the rounded corners joining such edges and one of the side edges of each sheet. By a proper adjustment of the runway rollers 11, and of the 35 guide brackets 26, each sheet is given the grinding contact necessary to round the portion of the sheet referred to. As the sheet approaches the first wheel, the portion A (Fig. 3) is engaged by the wheel. As the sheet is carried still further forward, the wheel contacts with the rounded portion B of the sheet, and finally as the sheet rides off of the grinding wheel in its movement to the left, the wheel contacts with the portion C of the sheet. In this manner, the grinding 40 of a straight surface and a curved surface is accomplished in the one operation, and during the movement of each sheet over the wheels, it moves freely in its guide rollers upon the brackets 45 26 and accommodates itself to the surface of the wheel.

50 Fig. 5 illustrates the adjustment of the apparatus in grinding body lights 49 having the curved surfaces 50. In this instance, the runway is positioned somewhat differently and the brackets 55 26 instead of being at an angle to the vertical, as is the case in the adjustment of Fig. 1, are placed in a vertical position, so that the glass sheets 48 in their movement over the grinding wheels move in a right line vertically instead of 60 at an angle to the vertical.

65 Fig. 6 illustrates the adjustment of the apparatus employed in grinding body lights having a straight edge 51 and the rounded corners 52, 53. In this instance, the rolls 11 of the runway sections are adjusted at the angle shown and the brackets 26 occupy the position shown in the figure. As a sheet approaches a wheel, its corner 52 engages the wheel and is ground, after which the straight edge 51 passes over the wheel, 70 and as the plate descends in its movement away from the wheel, the corner 53 is ground. It is thus possible to grind straight or curved edges or practically any combination of the two.

What I claim is:

75 1. The combination with a driven edging wheel

having a groove in its periphery and mounted for rotation about a horizontal axis, of runways leading to and from the wheel below the top of the wheel adapted to support the edge of a vertical sheet of glass which is to be edged, an endless driven drag member movable past the wheel at the side thereof, and bracket means secured to the drag member and provided with guide means arranged to support the sheet slidably in a vertical plane and guide it in a right line as its lower edge moves along the runway and over the wheel.

2. The combination with a driven edging wheel having a groove in its periphery and mounted for rotation about a horizontal axis, of runways leading to and from the wheel below the top of the wheel adapted to support the edge of a vertical sheet of glass which is to be edged, an endless driven drag member movable past the wheel at the side thereof, and bracket means secured to the drag member and provided with guide means arranged to support the sheet slidably in a vertical plane and guide it in a right line at an angle to the vertical as its lower edge moves along the runway and over the wheel.

3. The combination with a driven edging wheel having a groove in its periphery and mounted for rotation about a horizontal axis, of runways leading to and from the wheel below the top of the wheel adapted to support the edge of a vertical sheet of glass which is to be edged, an endless drag chain movable past the wheel at the side thereof, guide rails at each side of the wheel in parallel with the drag chain, bracket means movable along the guide rails and secured to the chain, and guide means for the glass sheet carried by the bracket means for supporting such sheet in a vertical plane and arranged to guide it in a right line as its lower edge moves along the runway and over the wheel.

4. The combination with a driven edging wheel having a groove in its periphery and mounted for rotation about a horizontal axis, of runways leading to and from the wheel below the top of the wheel adapted to support the edge of a vertical sheet of glass which is to be edged, an endless drag chain movable past the wheel at the side thereof, guide rails at each side of the wheel in parallel with the drag chain, bracket means movable along the guide rails and secured to the chain, and guide means for the glass sheet carried by the bracket means for supporting such sheet in a vertical plane and arranged to guide it in a right line as its lower edge moves along the runway and over the wheel.

5. The combination with a driven edging wheel having a groove in its periphery and mounted for rotation about a horizontal axis, of runways leading to and from the wheel below the top of the wheel adapted to support the edge of a vertical sheet of glass which is to be edged, an endless drag chain movable past the wheel at the side thereof, guide rails at each side of the wheel in parallel with the drag chain, bracket means movable along the guide rails and secured to the chain, and guide means for the glass sheet carried by the bracket means for supporting such sheet in a vertical plane and arranged to guide it in a right line as its lower edge moves along the runway and over the wheel, said runway being adjustable vertically.

6. The combination with a driven edging wheel having a groove in its periphery and mounted for

- rotation about a horizontal axis, of runways leading to and from the wheel below the top of the wheel adapted to support the edge of a vertical sheet of glass which is to be edged, an 5 endless drag chain movable past the wheel at the side thereof, guide rails at each side of the wheel in parallel with the drag chain, bracket means movable along the guide rails and secured to the chain, and guide means for the glass sheet carried by the bracket means for supporting such sheet in a vertical plane and arranged to guide it in a right line at an angle to the vertical as its lower edge moves along the runway and over the wheel.
- 10 7. The combination with a driven edging wheel having a groove in its periphery and mounted for rotation about a horizontal axis, of runways leading to and from the wheel below the top of the wheel adapted to support the edge of a vertical sheet of glass which is to be edged, an 15 endless drag chain movable past the wheel at the side thereof, guide rails at each side of the wheel in parallel with the drag chain, bracket means movable along the guide rails and secured to the chain, and guide means for the glass sheet carried by the bracket means for supporting such sheet in a vertical plane and arranged to guide it in a right line and engaging the two side faces 20 of the sheet and the two upright edges thereof, said guide means being arranged so that the glass sheet is free to move in a right line direction at an angle to the vertical as the lower edge of the sheet moves along the runway and over 25 the wheel.
- 20 8. The combination with a driven edging wheel having a groove in its periphery and mounted for rotation about a horizontal axis, of runways leading to and from the wheel below the top of the wheel adapted to support the edge of a vertical sheet of glass which is to be edged, an 30 endless drag chain movable past the wheel at the side thereof, guide rails at each side of the wheel in parallel with the drag chain, bracket means 35
- 30 9. The combination with a driven edging wheel having a groove in its periphery and mounted for rotation about a horizontal axis, of runways leading to and from the wheel below the top of the wheel adapted to support the edge of a vertical sheet of glass which is to be edged, an endless drag chain movable past the wheel at the side thereof, guide rails at each side of the wheel in parallel with the drag chain, bracket means 35
- 35 10. The combination with a driven edging wheel having a groove in its periphery and mounted for rotation about a horizontal axis, of inclined runways leading to and from the wheel below the top of the wheel adapted to support the edge of a vertical sheet of glass which is to be edged, an endless driven drag member movable past the wheel at the side thereof, and bracket means secured to the drag member and provided with guide means arranged to support the sheet slidably in a vertical plane and guide it in a right line at an angle to the vertical as its lower edge moves along the runway and over the wheel.

WILLIAM OWEN. 40
